(57) CLAIM

The ornamental designs for the hair weight, as shown and described.

DESCRIPTION

This Cross-Reference is related to U.S. Utility patent application Ser. No. 15/804,580

FIG. 1 is a front view of a hair weight showing my new design;

FIG. 2 is a top plan view thereof;

FIG. 3 is a bottom plan view thereof;

FIG. 4 is a front view thereof; and,

FIG. 5 is a left side view thereof.

The broken lines in the drawing depicting the female face and hair are for illustrative purposes only and form no part of the claimed design.
